UNITED STATES PATENT OFFICE

SAMUEL S. KESTIN, OF NEW YORK, N. Y.

DESIGN FOR A BUCKLE

Application filed November 1, 1930. Serial No. 37,498. Term of patent 3½ years.

To all whom it may concern:

Be it known that I, SAMUEL S. KESTIN, a citizen of the United States, residing at New York, in the county of New York and State of New York, have invented a new, original, and ornamental Design for Buckles, of which the following is a specification, reference being had to the accompanying drawing, forming a part thereof.

Fig. 1 is a plan view of a buckle, showing my new design. Fig. 2 is a perspective view thereof.

I claim:

The ornamental design for a buckle, as shown.

SAMUEL S. KESTIN
